UNITED STATES PATENT OFFICE.

GEORGE J. GRIFFITHS AND EMMET M. INGERSOLL, OF WOODSTOCK,
ILLINOIS, ASSIGNORS TO THE OLIVER TYPEWRITER COMPANY, OF
CHICAGO, ILLINOIS, A CORPORATION OF ILLINOIS.

TYPE-WRITER CARRIAGE.

No. 829,106.

Specification of Letters Patent.

Patented Aug. 21, 1906.

Application filed March 28, 1905. Serial No. 252,518.

To all whom it may concern:

Be it known that we, GEORGE J. GRIFFITHS and EMMET M. INGERSOLL, citizens of the United States, and residents of Woodstock, in the county of McHenry and State of Illinois, have invented certain new and useful Improvements in Type-Writer Carriages; and we do hereby declare that the following is a full, clear, and exact description thereof, 10 reference being had to the accompanying drawings, and to the letters of reference marked thereon, which form a part of this specification.

This invention relates to improvements in 15 supporting means for the paper-guides, guide-rollers, and scale-bar of a type-writing machine carriage by which auxiliary supports are provided for the said paper-guides, the guide-rollers, and the scale-bar between 20 the ends of the same, so that in extra long carriages said parts will be prevented from bending or flexing outwardly or away from the platen in the operation of inserting the paper into or feeding it through the machine.

25 Our improvements are herein shown as applied to the carriage of an Oliver type-writing machine; but the same may be adapted to other machines to which they are applicable.

As illustrated in said accompanying drawings, Figure 1 is a view in front elevation of the paper-carriage of an Oliver type-writing machine; showing our improvements applied thereto. Fig. 2 is a cross-section of the carriage, taken upon line 2 2 of Fig. 1. Fig. 3 is a perspective view of the central part of a lower paper-guide. Fig. 4 is a face view of the auxiliary supporting devices in the central part of the carriage, the same being shown in face view and on a much enlarged 35 scale. Fig. 5 is an enlarged detail cross-section taken upon line 5 5 of Fig. 4. Fig. 6 is a perspective view of the holding-clip for the lower guide-roller separate from the other parts. Fig. 7 is a perspective view of the 40 supporting-arm for the lower guide-plate separate from the other parts. Fig. 8 is a perspective view of a device for holding the front guide-plate and scale-strip from bending or flexing outwardly, made in one piece 45 instead of in two separate parts.

As shown in the drawings, A designates as a whole the carriage of an "Oliver" type-writing machine, A' the platen thereof, and A² A³ A⁴ the presser-rollers by which the pa-

per is guided about the platen and by which it is held properly in place against the platen during the printing operation. Said carriage comprises in its general features end plates a a and longitudinal frame-bars a' a'. Upon the front edge of the front lower bar a' is formed the rack-bar a² of the letter-spacing mechanism.

B designates a curved guide-plate or paper-shield located at the front of the platen between the upper and lower front presser-rollers A² A³, by which the advance margin of a sheet of paper which is being inserted into a machine is guided as it passes from the lower to the upper presser-roller. The said front presser-rollers are mounted in a frame comprising end pieces C C and a longitudinal bar C', which extends between said end pieces. Said bar C' is connected with said end pieces by means permitting it to rock on its longitudinal axis, and the guide B is affixed at its upper margin to said bar and depends therefrom. Said guide is thus free to swing at its lower margin toward and from the platen. The shafts of said presser-rollers are rotatively mounted in the upper and lower ends 70 of said end pieces C C of the frame. The frame thus carrying the presser-rollers A² A³ and the guide-plate B is movably mounted in the carriage of the machine by means of studs a⁴ a⁴, projecting laterally from said end 75 pieces and entering forwardly-opening notches in the end plate a a of the carriage-frame. The parts thus described are held in place and pressed toward the platen by means of leaf-springs B' B', which are attached at 80 their lower ends to the carriage and bear at the upper or free ends against the ends of the guide-plate B, the springs permitting the frame, rollers A² A³, and the guide-plate to yield bodily away from the platen to accommodate the thickness of a number of sheets of paper and also permitting the lower edge of the guide-plate to yield away from the platen, 85 for the same purpose.

The lower presser-roller A⁴ and the lower guide-plate H are supported by two spring-arms arranged horizontally and adjacent to the end plates a a of the carriage and secured at their rear ends to lugs on said end plates, one of the arms being indicated by G and its supporting-lug a⁵ being shown in Fig. 2. D indicates a scale-strip which extends longitudinally over the platen at the rear of

the roller A² and is pivotally connected at its ends with the end pieces C C by pivots located near its forward edge, so that its rear edge may rise and fall, the rear edge of the 5 said scale-strip being held yieldingly pressed against the platen by the paper-guide fingers of the carriage, which bear at their forward ends on said scale-strip. E in the drawing Fig. 2 indicates one of said guide-fingers, 10 and E' the longitudinal supporting-bar for the guide-fingers. The construction of said frame and the manner of mounting the same and the rollers, guide-plate, and scale-strip on the carriage are substantially the same as 15 shown in the prior United States Letters Patent to Knapp, No. 693,033, granted on the 14th day of February, 1902, and need not be further described. Such other parts of the carriage illustrated, which constitute no 20 part of the present improvements, are not herein described, but are the usual parts of an Oliver type-writing machine.

Attached at its lower end to the carriage-frame and extending upwardly therefrom 25 is a supporting-arm F, the upper end of which engages the central part of the bar C' in a manner to prevent the central part of the bar and the guide-plate attached thereto from bending or flexing outwardly. Said 30 arm is also made of yielding character to permit the central part of the bar C' and the guide-plate to yield bodily outward with the end pieces C C when a thick sheet of paper or a number of sheets of paper are inserted 35 into the carriage, thereby being adapted to act with the springs E E to yieldingly hold the guide-plate as a whole pressed toward the platen. Said supporting-arm F in the instance illustrated consists of a flat leaf-spring 40 which is affixed at its lower end in any suitable manner to the longitudinal member a' of the carriage-frame and is engaged at its upper end with the bar C', which carries the guide-plate B, in a manner to prevent 45 the central part of said bar from both bending outwardly and rising. As herein shown said arm is provided at its upper end with a hook-shaped portion f, which hooks over the top of the bar C'. The arm is attached at its 50 lower end to the longitudinal member a' of the carriage in the instance illustrated, by means of a headed screw f', extending through a slot in the lower end of the arm and into the carriage-frame member. The 55 arm F is like that described and shown in our prior application, Serial No. 211,572, filed June 8, 1904.

The improvements constituting the present invention embody means for supporting 60 or holding properly in place the central or middle portions of the lower guide-roller A⁴, the lower guide-plate H, and the scale-strip D. Heretofore said lower guide-roller, lower 65 guide-plate, and scale-strip have been supported solely by the connection at their ends

with the parts which support the same, and in machines having extra large carriages it has been found that the lower feed-roller, lower guide, and the scale-strip tend to bend or flex at their central portions outwardly 70 away from the platen when outward pressure comes thereon, as when inserting a heavy sheet of paper or a number of sheets of paper into the machine, with resulting liability of 75 lessened efficiency of these parts in the feeding of the paper.

First referring to the means for holding in place the central part of the scale-strip D, I indicates a metal plate or clip which is secured to the outer face of the bar C' and extends upwardly therefrom and inwardly over the central part of the upper face-roller A³ to the scale-strip with which it has bearing contact. Moreover, said clip I is connected with the scale-strip by means of a pin or stud i on 80 the clip, which projects downwardly through a socket or hole in the scale-strip, so that the scale-strip is interlocked with the arm and held not only from bending or flexing upwardly, but from being horizontally shifted 85 or sprung at its center in either direction. Said clip I is shown as provided at its lower end with two laterally-extending arms i' i', which rest against the outer face of the bar C and are secured thereto by screws passing 90 through said arms, as illustrated, said clip baying at its central part between the arms i' i' an open space or notch into which extends the upper end of the arm F.

Inasmuch as the central part of said bar 95 C' is held from outward and upward movement by interlocking engagement of the upper end of the said spring-arm F therewith, connection of the central part of the scale-strip D with the said bar C' through the medium of the plate or clip I described will have the effect of also holding the central part of the scale strip from bending or yielding outwardly or upwardly, while the interlocking connection of the clip with the scale-strip 105 prevents its central part from being bent or flexed horizontally.

The upper guide-roller A² is preferably reduced in diameter at its part opposite the plate I, so as to form a groove a⁶ wide enough 115 to receive the part of the plate or clip I which passes over the said roller. The clip I may thereby be so arranged that it will not project outside of the surface of said guide-roller A².

Now referring to means for supporting or holding from outward bending or flexure the central parts of the lower guide-roller A⁴ and the lower guide-plate H a construction is provided, as follows: K indicates a supporting-arm which is attached to the main longitudinal bar of the carriage-frame and projects rearwardly therefrom with its free end in position to engage or form a bearing 125 for the central part of the lower feed-roller, 130

which latter is grooved or reduced in diameter so as to form an annular cylindric journal or bearing-surface a^2 , which engages a concave bearing-surface k on the rear or free end of said arm. The said concave bearing-surface is preferably formed by curving the rear end of said arm, so that it will fit against the journal a^2 at the bottom and rear part of the same. In the particular construction of the parts illustrated the forward end of the supporting-arm K extends beneath the horizontal bar a' and is provided with a slot k' , through which is inserted a holding-screw k^2 , by which the arm is adjustably connected with said bar.

The arm K , arranged as described, with its end portion in contact with the bearing-surface a^2 at the part thereof opposite or remote from the platen A' , serves to resist the outward movement of the central part of the lower feed-roller in a direction away from the platen. Said arm K is made of spring metal, so that it acts with spring-pressure against the lower presser-roller and coacts with the supporting-springs $G G$ of said roller to press or hold the same yieldingly against the platen.

A device is employed for supporting the central part of the lower guide-plate H as follows: L is a secondary supporting-arm which is attached to the rear or free end of the arm K and extends forwardly and upwardly therefrom in position for bearing-contact with the bottom surface of said guide-plate H . Said arm L is shown as shaped or formed to conform to the curvature of the outer curved or bearing portion k of the arm K and as secured to the outer or lower face thereof, with its forward end extending through a longitudinal slot k^3 , formed in the said arm K between said curved bearing portion k thereof and its horizontal part, which is secured to the cross-bar a' of the carriage. The forward or free end of said arm L is shown as shaped to form a bearing portion l' , which rests and fits against the curved lower portion of the guide-plate H , the intermediate portion of said supporting-arm L between its rear curved part l and said forward part L' being inclined upwardly and forwardly, as clearly shown in the drawings. In order to hold the bearing end l' of the arm L from shifting laterally on the guide-plate H , the stiffening bar or rib h , which is usually provided on the bottom surface of said guide-plate, is shown as provided with a notch h' , Fig. 3, equal in width to the end l' of the supporting-bar L , and within which said end l' fits or rests. The said arm L is also preferably made of spring metal, so that the resiliency of said arm, together with that of the arm K , to which it is attached, affords considerable degree of yielding movement in the central part of the plate H , permitting said plate to yield downwardly or away from the platen, when the ends of said guide-plate, together with the ends of the roller A^4 , are depressed by the downward movement or yielding of the spring-supporting arms $G G$, by which said guide-plate and the said lower roller are sustained.

While the means illustrated for holding the scale-strip from rising or bending in its center embrace a clip attached to the bar C' and a supporting-arm F on the carriage engaging said bar C' , so that the said clip constitutes, in effect, a continuation of said arm F , yet the same general result will be obtained if the said clip be directly attached to or forms an extension of the arm F instead of being made separate from said arm and connected with the same through the medium of the said bar C' . A construction of this kind referred to is shown in Fig. 8, in which N indicates an arm adapted to be attached to the frame-bar a' in the same manner as the arm F , hereinbefore described, and provided at its upper end with an integral upward extension N' , terminating in a horizontally-bent part which is provided near its rear end with a pin or stud n and which is adapted to extend to and engage the scale-strip D in the same manner as does the clip I , hereinbefore described. The said arm N is in this instance provided at its side edges with rearwardly-bent integral prongs $n' n'$, located in position to engage the bar C' , so as to hold the latter from rising, said prongs taking the place of the hooked upper end f of the said arm F . (Shown in Figs. 1, 2, 3, and 4.)

We claim as our invention—

1. The combination with a paper-carriage, a platen, a longitudinal paper-guide and a scale-strip, of a supporting-arm attached to a longitudinal member of the frame and engaging the paper-guide, and a clip constituting a continuation of the supporting-arm and adapted to bear against the scale-strip at a point between its ends to hold it from springing outwardly away from the platen.

2. The combination with a paper-carriage, a platen, a longitudinal paper-guide and a scale-strip, of a supporting-arm attached to a longitudinal member of the frame and engaging the paper-guide and a clip which forms a continuation of the said supporting-arm and has interlocking engagement with the scale-strip.

3. The combination with a paper-carriage and a platen, of a longitudinal paper-guide arranged vertically in front of the platen, a scale-strip arranged horizontally over the platen and a clip attached to and rising from the paper-guide and having its upper end bent rearwardly and bearing on the scale-strip to hold the latter from bending or flexing upwardly at its central part.

4. The combination with a paper-carriage, a platen, a scale-strip, a longitudinal paper-guide pivotally connected at its ends with the carriage-frame and springs applied to press the swinging edge of the guide toward the

- 4 platen, of an arm affixed to the carriage-frame and engaging the paper-guide between the ends of the latter and at a point opposite its pivotal axis, and a clip attached to the 5 paper-guide and bearing on the scale-strip so as to hold the same from bending outwardly between its ends.
5. The combination with a paper-carriage, a platen, a scale-strip, a longitudinal paper- 10 guide, a longitudinal bar to which said paper-guide is attached and which is pivotally connected at its ends with the carriage and springs applied to the paper-guide to press the same toward the platen, of an arm attached to the carriage-frame and having interlocking engagement with said longitudinal bar at a point between its ends and a clip attached to the said longitudinal bar and bearing on the said scale-strip at a point between 15 its ends.
6. The combination with a paper-carriage, a platen, a longitudinal paper-guide and a scale-strip, of a clip attached to the paper-guide and extending over the outer face of 20 the scale-strip; said clip being provided with a stud and the scale-strip with a socket to receive said stud.
7. The combination with a paper-carriage, a platen, a longitudinal paper-guide, a scale- 25 strip and a guide-roller located between the paper-guide and the scale-strip, of a clip extending from the paper-guide over the roller to the scale-strip, said guide-roller being provided with a circumferential groove to receive the part of the clip which extends over 30 said roller.
8. The combination with a paper-carriage and a platen, said paper-carriage having a longitudinal frame member located at the 35 front thereof below the platen, of a guide-roller beneath the platen, horizontally-arranged spring-arms attached at their rear ends to the rear part of the carriage at the ends of the latter, and having at their forward end bearings for the ends of the said 40 guide-roller, and an auxiliary spring-supporting arm attached to the central part of said longitudinal frame member and extending rearwardly and upwardly therefrom, with its 45 rear end pressing on the central part of the guide-roller to prevent outward bending or flexing thereof.
9. The combination with a paper-carriage and a platen, said paper-carriage having a 50 longitudinal frame member located at the front thereof below the platen, of a guide-roller beneath the platen, horizontally-arranged spring-arms attached at their rear ends to the rear part of the carriage at the 55 ends of the latter, and having at their forward ends bearings for the ends of the said guide-roller, and an auxiliary spring-supporting arm attached to the central part of said longitudinal frame member and extending 60 rearwardly and upwardly therefrom, with its 65 rearward end bearings for the ends of the said guide-roller, and an auxiliary spring-supporting arm attached to the central part of said longitudinal frame member and extending rearwardly and upwardly therefrom, with its
- 70 rear end pressing on the central part of the guide-roller to prevent outward bending or flexing thereof, said guide-roller having a central annular bearing - surface or journal of smaller diameter than the body of the roller, 75 and the auxiliary supporting-arm having a concaved bearing-surface for contact with said journal on the roller.
10. The combination with a paper-carriage, a platen, a guide-roller and a longitudinal 80 paper-guide adjacent to said guide-roller, of a supporting-arm attached to a longitudinal member of the carriage-frame and bearing on the roller between ends of the latter to hold said roller from outward bending or flexure, 85 and a secondary supporting-arm attached to the first-mentioned supporting-arm and bearing on the said paper-guide also hold the latter from outward bending or flexure.
11. The combination with a paper-carriage 90 having a lower longitudinal frame member, a platen located above said longitudinal frame member, a guide-roller located beneath the platen at the rear of said frame member, and a lower, longitudinal paper-guide located beneath the platen in front of the said guide-roller, of a supporting-arm attached to the 95 said frame member and extending rearwardly therefrom with its rear end in position to bear upwardly on the guide-roller, and a secondary supporting-arm attached to the first-mentioned supporting-arm and extending forwardly therefrom with its forward end in 100 position to press upwardly on the said paper-guide.
12. Supporting means for a guide-roller and a paper-guide, consisting of a supporting-arm, having a slot between its ends and a secondary supporting-arm attached to one end of said first-mentioned arm and extending through the slot therein, with its bearing end directed oppositely from the bearing end of the first-mentioned supporting-arm.
13. The combination with a paper-carriage 105 provided with a longitudinal frame member, a platen, a guide-roller and a longitudinal paper-guide, of a supporting-arm attached at one end to the frame member and adapted to bear at its free end against said guide-roller, said arm having a slot between its 110 ends, and a supporting-arm for the paper-guide attached at one end to the outer face of the outer end of the said first-mentioned supporting-arm and extending through said slot with its other end in position to engage 115 the said paper-guide.
- In testimony that we claim the foregoing as our invention we affix our signatures, in presence of two witnesses, this 23d day of March, A. D. 1905.
